MAURICE R. SMITH, OF KANSAS CITY, MISSOURI.

MAILING TUBE.

Application filed June 26, 1926. Serial No. 118,685.

This invention relates to mailing tubes.

The invention is capable of general application in the art of mailing tubes and similar devices, and is of particular importance as a fluid mailing tube. There are a number of industrial organizations that maintain laboratories for the analysis of specimens submitted to them, and as the specimens are usually fluids it is necessary that the containers be fluid-tight. Glass bottles have been used in the past for the purpose, being inserted in an outer housing for mailing. These have proven ineffectual as containers, as, although the glass is not easily affected by the fluid content, yet they are readily and inconveniently broken, with disastrous results, are difficult to clean and to keep sterile, have small openings rendering the bottles difficult to fill, and, of great importance, they are too heavy for economical use, particularly in view of the high postal rates.

Among the objects of this invention are, to provide a mailing tube of great durability and resistance to breakage; to provide a mailing parcel of great efficiency but with a minimum of weight; to provide a specimen container having a maximum mouth or filling opening; to provide a specimen container of insignificant weight that may be readily filled, emptied, cleaned and sterilized; to provide a metal container which is not affected by the specimen with which it is filled and which does not affect the specimen; to provide a unitary receptacle and mailing tube; to provide a unitary receptacle and mailing tube arranged to be fluid tight and to be maintained so by a novel closure device, and many other objects and advantages as will be more apparent as the description proceeds.

In the accompanying drawings, Fig. 1, represents a longitudinal section through a mailing tube in accordance with this invention. Fig. 2, represents a similar view of a modified form of the invention, Fig. 3, represents a section through one form of unitary receptacle and mailing parcel, and Fig. 4, represents a further modification of the form shown in Fig. 3.

Figure 5 is a horizontal cross-section of the device of Figure 2.

Figure 6 is a vertical cross-section of another modification.

It will be recognized that there are many things other than fluids that may be used in connection with the containers of this inven-

tion, and the uses to which the containers may be put need not involve mailing. For the purpose of this description only, and without any desire so to limit the invention, the invention will be considered in the light of the practice of laboratories conducting analysis of urine. The practice is similar in many respects to the transmission of oil specimens, or of blood for Wassermann tests, 65 usually enclosed in Keidel tubes.

A mailing tube with an enclosed bottle having return addresses and the names of the person to whom it is sent, or some such data, is either handed to the patient by a physician, or mailed by the laboratory. The mailing tube is opened, the bottle removed, filled with a specimen, the outer wrapper of the tube is removed, disclosing the address of the laboratory to which it is to be mailed, the 75 bottle is inserted, and the specimen mailed to the recipient.

Where glass bottles are used, they must be very thick to withstand any shocks at all, and this increases the weight and the cost of mailing the entire parcel, both ways. The necks of the bottles are of restricted area making them difficult to fill, and cleaning of the bottles is difficult, and due to the frangibility of the glass the breakage rate is high when 85 they are attempted to be sterilized. Altogether they are very unsatisfactory.

Referring now to the drawings, this invention consists primarily of a metallic fluid container 10, of cylindrical form open at one end as at 11 to form a wide mouth, and closed at the bottom as at 12. This may be formed by a die, of any desirable metal. It has been found that aluminum answers every requirement, being durable, easily worked to the desired shape, being extremely light, and of such rigidity as to withstand normal crushing strains. It is to be noted that the sides of the aluminum bottle thus formed do not converge, but remain of the same diameter throughout the bottle. The wide mouth 11, being of the same diameter as the bottle provides an easily filled entrance, into which liquids can be quickly poured and the bottle filled without spilling the liquids during the process. Further the wide mouth renders the task of cleaning the bottle very simple, and being of metal the entire bottle may be boiled for sterilization with perfect freedom, as it will not break.

Associated with the bottle is a cork or stopper 13, preferably with gradually ta-

pered sides, as at 14, and preferably of such length that when frictionally engaged in the mouth 11, of the bottle, the top or upper end of the cork extends appreciably above or 5 beyond the bottle in position to be engaged by the cap of the outer housing to be later described.

For mailing purposes, the bottle is inserted in a mailing tube which may be of 10 any desired form and material. As shown in Fig. 1, the tube 15 may be of cardboard or fiber material, cylindrical in shape, closed at the bottom by the permanent metal closure 16, the open end of the tube being bound by 15 a ferrule or collar 17, carrying thread 18, arranged to threadably receive the cap 20, having integral flange 21 threaded as at 22. The construction of Fig. 2, is very similar to 20 Fig. 1, except that the outer housing 24 is a closed cylinder of metal, such as aluminum, formed in any desirable manner, and with a thread 25 cast or turned on the upper open end. The cap for a closure may also be of 25 aluminum as shown at 26, with integral flange 27 and thread 28, or the punched metal cap shown in Fig. 1 may be used. In either form, and for lightness and general utility I prefer the outer housing to be 30 made of aluminum, which is rigid, and amply strong to resist ordinary shocks incident to its use, and for another very important reason. With the cardboard tube as used heretofore, any leakage of a specimen from the bottle saturated the cardboard and rendered it unfit for further use. With the 35 housing of this invention the outer casing may be sterilized and used as frequently as desired.

In either case, I prefer to provide a thin 40 layer of resilient material 30 in the bottom of the outer housing, upon which the bottle of my invention rests, in such position with the cork inserted, that the upper end of the cork extends a trifle beyond the end of the 45 tube. In this position, application of the cap and screwing it up on its threads imposes the lower surface of the cap upon the end of the cork forcing the cork further into the bottle, and preventing its withdrawal, and also exerts longitudinal pressure 50 on the entire bottle, through the cork, pushing it against the elastic or resilient layer at the bottom of the tube, so that the bottle is resiliently held against shocks and 55 is prevented from rattling about in the tube. The advantages of this will be obvious.

In the forms of the invention disclosed in 60 Figs. 3 and 4, a single unitary tube is provided which forms a combination of receptacle of mailing tube. As shown in Fig. 3, a cylindrical tube, preferably of aluminum as at 31, has a closed bottom as at 32, and is of uniform diameter from the bottom to very close to the top, where an inturned collar or bead 33 is provided, of appreciably

smaller diameter than the tube, and beyond the bead a threaded terminus 34 is formed, which may be of the same diameter as the lower portion of the tube below the bead. A cork 13' is provided arranged for frictional seating on the valve seat formed by the inner surface of the bead, and which is arranged to be forced into seating position on the bead by pressure from the cap 20' is screwed upon the threads of the terminus 34. The advantages of this form of the invention are obvious, but they include a large pouring opening or funnel, so that filling the receptacle is made quite easy, and, as the cork is firmly held by the cap and by friction, there is no chance of leakage. The elimination of the outer housing, besides being economical in the purchase of the devices, is of tremendous value in view of the decrease effected in mailing costs. 85

In the form shown in Fig. 4, the outer wall of the tube 35 is straight, but has an internal annular bead cast or formed in the metal as at 36, to form the shoulder to receive the cork 37, and has the closed bottom 39, and upper threaded portions 38 arranged to receive a threaded cap 40 in the same manner as the form shown in Fig. 3. 90

The cylindrical bodies provided in the several forms are arranged in any desired 95 manner to receive external stickers or labels 41, bearing mailing and other data as may be required.

In the form of the invention disclosed in 100 Fig. 6, the lower bottle portion 42 terminates in the cork receiving bead 43, and the upper filling opening 44, is closed by the threaded screw-cap 45, preferably carrying a cork disc 46, or similar sealing medium, to bear against and seal the mouth 47 of the filling opening. The cork 48, which may be 105 relatively short has a short cork-screw 50 screwed into it in position to be grasped either by the fingers of the operator, or by a mechanical device such as a hooked instrument, (not shown), and the rest of the space in the filling opening 44 is filled with more or less compacted fibrous material, such as 110 cotton, which is highly absorbent to prevent leakage from the bottle mouth if perchance the cork 48 does not form a perfect seal, or becomes dislodged in transit. The absorbent factor, in connection with the additional seal 46 provides an absolutely tight 115 and leak-proof structure which may be used with perfect safety, and which will accord 120 with the postal regulations.

While the preferred material for the bottles and containers is aluminum, yet any alloy of aluminum might also be used to 125 good advantage.

The invention provides an efficient container and mailing tube, arranged to receive liquids of various sorts, as well as 130 solids when desired; that is light in weight

with great savings in postage; which is strong, simple, practically unbreakable, and which is fluid-tight, due to the novel arrangement of the closure members.

5 I claim as my invention:

1. A unitary mailing tube, comprising a lower liquid receiving receptacle, an inwardly extending annular shoulder formed in the tube to form the mouth of the liquid receiving receptacle, a cork frictionally inserted into the opening in the shoulder to form a liquid tight closure for the receptacle, a hook formed in the cork for withdrawing it from its frictionally held position, said cork so arranged as to leave a space between it and the end of the tube above the shoulder, absorbent means com-
- 10
- 15

pacted in said space, and a cap engageable with the end of the tube.

2. As a unitary mailing tube, a light metallic cylinder having a closed end and an open end, an annular curved bead extending into the tube near the open end and arranged to frictionally receive a cork extending below the bead and above the open end, threads formed externally on the cylinder adjacent the bead, an internally threaded cap arranged to engage the threads and having a portion in engagement with the cork to maintain the frictional engagement thereof.
